FOLDING MACHINE

William Ward Davidson, Evanston, Ill., assignor to Davidson Manufacturing Corporation, a corporation of Illinois

Application August 9, 1937, Serial No. 158,100

15 Claims. (Cl. 270—68)

In printing plants handling a variety of types of work the provision of folding machines which will meet all of the requirements has been a severe problem. The folding to be accomplished may vary all the way from a single fold, as in letters, pamphlets and the like, to a complicated series of folds some in one direction and some in another, such as may be used in folding forms of many pages for books. The folding of book sections varies widely depending on the number of pages and the manner of binding.

In the past a single machine capable of performing various series of folds including right-angle folds have been extremely complicated and have necessarily included many folding units which would lie idle most of the time, when running simpler folds. Idle folding units not only represent an expensive investment but also furnish opportunities for the paper passing through the machine to jam and furthermore require many extra adjustments every time the machine is changed for a different folding operation.

According to the present invention a greatly simplified machine is provided having extreme flexibility because of new features and particularly because of a new combination of features. In my prior Patent No. 1,620,444 I disclosed one manner of obtaining flexibility, consisting in the provision between two folding units of a conveyor for carrying the sheet from one unit to the other, together with means for turning the sheet 90° or not turning it at all at will. In its illustrated form the present invention uses this combination in improved form, preferably with a second conveyor capable of turning the paper and with a delivery table or stacking unit which may be attached adjacent to any folding unit so that the sheet may be ejected from the machine at the earliest possible moment, thus reducing the number of idle folding units which the completely folded sheet must pass and the number of adjustments which must be made to cause the sheet to pass all the way through the machine without being further folded. The combination of the means for turning the sheet after each fold so as to enable subsequent folds to be made in any desired direction and the means for ejecting the sheet to a delivery table at any point is the only way of providing complete flexibility with the minimum number of adjustments and the minimum danger of the sheets jamming as they pass through the machine. Further simplification is secured by providing a simplified form of conveyor table capable of turning the sheet in either direction.

From the foregoing it is evident that an object of the invention is to provide a folding machine of greater flexibility for accomplishing any one of a variety of series of folds and preferably one in which the sheet being folded, passes fewer idle folding units than in former folding machines capable of making the same variations of use.

Further objects and advantages of the invention will appear as the description is read in connection with the accompanying drawings, in which:

Fig. 1 is a vertical longitudinal sectional view taken through the machine approximately on the line 1—1 of Fig. 7, the stacking unit being fragmentarily shown in one position in full lines and in two alternative positions in dotted lines.

Fig. 2 is a fragmentary plan view of the stacking unit showing its mounting on the main frame.

Fig. 3 is a fragmentary vertical sectional view on a larger scale showing the construction of the stacking unit and showing its attachment to the remainder of the folding machine, being taken approximately on the line 3—3 of Fig. 2 and some parts being omitted for the sake of clarity.

Fig. 4 is a fragmentary sectional view taken approximately on the line 4—4 of Fig. 2 and showing the driving mechanism for the stacking unit.

Fig. 5 is a fragmentary bottom view of the stacking unit.

Fig. 6 is a transverse sectional view showing the receiving end of the stacking unit and taken approximately on the line 6—6 of Fig. 5.

Fig. 6a is a fragmentary sectional view taken on line 6a—6a of Fig. 4.

Fig. 7 is a fragmentary sectional view taken approximately on the line 7—7 of Fig. 1, showing the top of the turning table with a sheet of paper shown in dotted lines in three positions.

Fig. 8 is a view similar to Fig. 7 but showing the machine arranged for turning the paper in the opposite direction.

Fig. 9 is a transverse sectional view taken approximately on the line 9—9 of Figs. 1 and 7.

Fig. 10 is a similar view taken approximately on the line 10—10 of Figs. 1 and 7.

Fig. 11 is a fragmentary sectional view taken approximately on the line 11—11 of Figs. 1 and 7.

Fig. 12 is a perspective view of the pressure strip for pressing the paper against the conveyor belt to insure proper movement of the paper.

Fig. 13 is a similar view of the paper guide which the paper strikes and along which it slides.

Figs. 14 to 28 are perspective and diagrammatic illustrations of the machine with different adjustments and of a variety of folds which may be made by such adjustments. Thus, Fig. 14 shows the stacking unit associated with the first feed unit for making a single fold such as is shown in Fig. 15. Fig. 16 shows the stacking unit associated with the second folding unit for folding a sheet of paper twice, these folds being either at right angles to one another as shown in Figs. 18 to 20. Fig. 21 shows the stacking unit associated with a third folding unit for folding each sheet of paper at least three times, with parallel folds as shown in Figs. 22 to 25, for example, or with folds first in one direction and then at right angles thereto as shown in Figs. 26 and 28, or with folds in one direction and then at right angles thereto and then in the first direction as shown in Fig. 27. The illustrated folds are merely representative of the almost unlimited number of folds which can be secured, especially if more than a single folding unit is provided at each folding position on the machine.

A preferred embodiment of the invention has been shown in the drawings and will hereinafter be described, all as required by sec. 4888 of the Registered Statutes, but the appended claims are not to be limited by the specific disclosure unless required by the prior art.

As seen in Fig. 1, the entire folding machine may be supported by a frame 1 and, briefly stated, includes a feed table indicated more or less diagrammatically at 2, a conveying and turning table indicated as a whole by the numeral 3, a second conveying and turning table indicated as a whole by the numeral 4, with folding units 10, 20 and 30 positioned at the end of each table, scoring rolls 5 and 6 adjacent to the folding units 10 and 20, and with an ejecting and stacking unit or stacker 7 optionally positioned adjacent any folding unit to receive the folded sheet therefrom.

Folding units

Although the folding units may be of any type, that illustrated is the buckle type and it is the same at all positions. The reference numerals begin with 11 in unit 10, 21 in unit 20, and 31 in unit 30, the last digits being the same for like parts. The paper is fed to the folding unit 10 from the table 2 either by hand or more commonly by an automatic feeding device. The construction of the folding units is seen best in Fig. 3, in which the folding unit is that at the third position, the feeding and folding rolls being numbered 31, 32 and 35. The rolls 31 and 32 first receive the paper and feed it into the buckle chute 33, which it enters freely until it strikes the paper stop 34 which stops the forward edge of the paper. Since the feeding action of rolls 31 and 32 continues, the paper necessarily buckles into the space between rolls 32 and 35. The buckled sheet is thus caught by these two rolls and drawn in between them to crease the buckled sheet and thus complete the fold. The position of the fold is determined by the position of the paper stop 34 which may be adjusted by loosening the clamping nut 36. The two rolls 32 and 35 continue to draw the paper down between them, drawing it out of the buckle chute 33 and feeding it to the next unit of the machine. In Fig. 1 the sheet passes from the corresponding rolls 12 and 15 to the scoring rolls 5, one of 75 which may be grooved or formed of rubber to

receive a blade-like member on the other. It may be observed that the scoring is not necessary before the first fold but is usually desirable for subsequent right-angle folds to insure a smooth fold of the already folded paper. If there is to be no subsequent right-angle fold, the scoring rolls may be separated or moved to one side so as not to score.

Deflectors

Below the scoring rolls 5 and below each folding unit is a deflector 46 or 47 for directing the paper in the desired direction away from the folding unit. The deflector 47 below folding unit 30 is fixed to direct the folded sheet to the ejecting folds 48 and 49 of the stacking unit. The deflectors 46 at the first two folding units 10 and 20 in Fig. 1 are shiftable between the position shown in full lines and that shown in dotted lines. In the full line position the deflector guides the folded sheet toward the next folding unit or, more specifically, onto the conveyor and turning table 3 or 4. When a deflector 46 is in the dotted line position it guides the folded sheet directly to the ejector rolls 48 and 49 which will then have been moved with the stacking unit 7 to the position shown in dotted lines adjacent the deflector 46 in question. It is evident therefore that the machine may be adjusted to eject the folded sheets immediately after they leave any one of the three folding units. In other words, if the sheet is to be folded only once, it may pass through the folder 10 and then immediately to the stacking unit 7. If it is to be folded twice, it may pass through the first two folders 10 and 20 and then immediately to the stacking unit 7.

The stacking unit

As previously noted, a sheet which has been completely folded is passed to the ejector rolls 48 and 49 by one of the deflectors 46 or 47. The rolls 48 and 49 feed the folded sheet under the resilient holding fingers 51 and onto the feed belts 52 which run along the delivery table 53. The belts 52 are driven by drive roll 54 and extend around idler roll 55, both of which are carried by the stacker frame 56, as are the ejector rolls 48 and 49. The belts 52 run over a belt tightening shaft 57 adjustably supported by arms 58 secured to the frame 56. The tightening shaft 57 carries an inverted U-shaped belt guide 59 for each belt. The belts may be positioned at any desired point laterally of the table 53 by loosening the set screw 60 and sliding the belt guide 59 to the desired position.

That which has heretofore been called the upper ejecting roll 48 is in reality a series of small pressure rollers each pivotally carried by a pin 61 in an arm 61' which is pivoted on a shaft 79 urged in a direction toward the ejecting roll 49 by a spring 62 seen in Fig. 3. The tension of the spring may be adjusted by loosening a set screw 63 and rotating the block 64 on the shaft 79. The lateral position of the unit may be adjusted at the same time by sliding block 64 along shaft 79, arm 61' straddling block 64, and hence moving with it. The spring fingers 51 are each carried by a collar 65 carried on a split extension of pin 61 which may be expanded by a screw 65' to grip the collar 65 and hold the spring finger 51 in any desired position to exert a predetermined tension on the folded sheets passing thereunder.

Detachability of stacking unit

As previously noted, an important feature of the invention is the ability to place the stacking unit adjacent each of the folding units so as to receive the folded sheet directly therefrom if desired. The manner of attaching the stacking unit to the main frame 1 is seen best in Figs. 2, 3 and 5. The frame 56 is provided on each side with a bifurcated extension 66 which engages a pin 67 mounted on frame 1 as seen best in Fig. 2. The frame 56 also carries a pin 68 on each side adapted to extend into a suitable hole in the frame 1 as is also seen best in Fig. 2. Each pin 68 is urged into its engaging position by a leaf spring 69 and may be withdrawn therefrom by a releasing lever 10 which is rockably secured to the frame 56 by a screw 11. The lever 10 operates the pin 68 through a screw 13 which fits both the lever 10 and the spring 69 with sufficient play to prevent binding. As is evident from Fig. 5, the actuation of the handles 72 of lever 10 in the direction of the arrows thereon will draw the pins 68 out from the frame 1, thus permitting the entire stacking unit to be slipped away from the frame 1 and the remainder of the folding machine, the bifurcated extensions 66 slipping freely away from the pins 67. In reinserting the stacking unit at another position it is merely necessary to slip the bifurcated extensions 66 onto the pins 67 at the other position, align the pins 68 with the corresponding holes in the frame 1, and release the handles 72 to permit the springs 69 to press the pins 68 into these holes. The stacking unit is thus secured in place quite firmly.

Drive for stacking unit

It is desirable that the drive be such that it will be automatically connected and disconnected as the stacking unit is attached to and removed from the main frame. In connection with each of the folding units there is provided on the frame 1 a gear 16 (Fig. 4) which is driven in any suitable manner with the folding unit. In the case of the last folding unit 30 the gear 16 may be on the shaft of the folding roll 35; in the other folding units it may be on a scoring roll shaft. The detachable frame 56 carries an idler gear 17 which is positioned to mesh with the gear 16 when the stacking unit is in place. It will be observed that the gear 17 is somewhat under the gear 16 since the stacking unit will usually be shoved into engagement with pin 67 first and then swung upwardly about this pin to its final position. This upward swinging movement will bring the gear 17 into mesh with the gear 16. The gear 17 drives a gear 18 which may rotate on a shaft 19 carried by the frame 56. The gear 18 performs two functions, rotating the gear 80 fixed on the shaft 81 of the lower ejecting roll 49, and also turning an eccentric 82 which may be the hub of the gear 18.

The eccentric 82 reciprocates a follower link 83 which is pivoted to a segment 84 which is pivoted on the shaft 85 of the drive roll 54 for the belt 52. The segment 84 carries a pawl 87 which is urged by a suitable spring against a ratchet wheel 89 keyed to the shaft 85. It is thus seen that with every revolution of the gear 18 and its eccentric 82 the segment 84 is drawn upwardly and thrust downwardly. In its upward movement the pawl 87 rides over the teeth of the ratchet 89, but on its downward movement they engage the teeth and turn the ratchet 89 and hence drive the belts 52 a suitable distance in the forward

direction. A suitable pawl might be provided if desired to prevent reverse movement of the ratchet wheel 89, but the friction will usually be great enough to make such a pawl unnecessary. From the foregoing it is seen that the gear 18 drives the ejecting roll 49 with a continuous movement and drives the delivery belts 52 with an intermittent movement. This has the effect of stacking the folded leaflets in the well known overlapping manner seen in Fig. 14.

10

Conveying and turning tables

If more than one fold is desired in the sheet the deflector 46 below scoring rolls 41 and 42 will be set as shown in full lines in Fig. 1 to 15 guide the folded sheet onto the conveying and turning table 3 which will feed the sheet to the second folding unit or, more specifically, to the rolls 21 and 22 thereof. If it is desired that the fold formed by this second folding unit be at 20 right angles to the first fold, this can be accomplished by turning the sheet through 90°. According to the present invention the turning of the sheet is accomplished by an improved form of table, construction of which is best seen from Figs. 1, 7, and 9 to 13. The table includes a table top 91 which may be supported from the frame 1 in any suitable manner as by brackets 92 and bar 94, seen best in Fig. 10. A feed belt 95 slides over table top 91, being driven by roll 96. The 30 belt passes around an idler roll 97 at its lower end and may be tightened and positioned laterally of the table by tightener and guide 98 similar to the tightener 51-58-59 of Fig. 3.

The folded sheet is passed onto the belt 95 from the deflector 46 and is carried under a guide strip 101 which is positioned by bracket 102 sliding on bar 103 and bracket 104 sliding on bar 105. The strip is positioned directly over the belt 95 wherever the belt may be positioned by 40 belt guide 98 and is secured in this position by set screws 106. The guide strip 101 may be provided with any means such as the marbles 107 for pressing the sheet against the belt 95 with relatively little friction, so as to insure the 45 proper movement of the sheet by the belt.

Resting on the table top 91 and preferably extending under the belt 95 is a paper guide 111 seen in Fig. 13. This paper guide is positioned properly with respect to the belt 95 and guide strip 101 by a clamp 112 secured at any position on the bar 105 by a set screw 113. The paper guide 111 includes a bottom plate portion 114 on which the sheet slides and an edge guiding flange 115 along the inside of which the edge of the sheet slides after the sheet is turned. The edge guide 115 terminates in its upper end with a shoulder 116 forming a turning stop beyond which is an extension 117 which forms a guide over the sheet to insure that the sheet properly engages the shoulder 116.

In Fig. 7 three positions of the paper sheet being turned are shown in dotted lines. At 121 the sheet has been dropped onto the belt 95 and is being moved forwardly by it toward the shoulder 116. At 122 the sheet has struck the shoulder 116 which stops one end of the sheet and the belt 95 has carried the other end of the sheet forwardly, thus turning the sheet. At 123 the belt has turned the sheet through 90° and 70 has carried it beyond the shoulder 116. The lateral inclination of the belt 95 is now pressing the sheet against the edge guiding flange 115, thus insuring the accurate lateral position of the sheet and also insuring that it is turned to exactly 75

90°. To be sure that the sheet does not jam, a pressure roller 124 supported from the guide strip 101 by spring urged arm 125 may be provided to press the paper firmly against the belt 5 95. An additional roller 128 is supported by pivoted arm 129 carried by a post 130 on guide extension 117. This roller aids in accomplishing the smooth turning of the sheet tending to start the sheet turning momentarily before it strikes the shoulder 116 so that there is no danger that the shoulder 116 will mar the edge of the sheet, and preventing the sheet from bouncing away from shoulder 116.

15 *Reversed turn*

For some folding effects it is desirable to turn the sheet in the opposite direction from that illustrated in Fig. 7. This may be accomplished as seen in Fig. 8 by providing a paper guide 211 20 similar to the paper guide 111 but positioned on the opposite side of the machine and by changing the belt 95 and guide strip 101 to position them near and incline them toward the paper guide 211. The guide strip 101 may be shifted for this purpose by loosening the set screws 106. The belt 95 may be positioned laterally by sliding the belt guide 98 along on its supporting shaft as described in connection with the belt tightener 59.

In order to incline the belt 95 in the opposite direction, as shown in Fig. 8, it is necessary to reverse the angular position of the rolls 96 and 97 carrying this belt. To this end the rolls 96 and 97 are journaled in bearing blocks 136 which are pivoted to slide bars 137 and 138. As seen 35 best in Fig. 10, the slide bars are supported by and slide with respect to bracket 92. A handle 139 may be rigidly secured to the slide bar 137 and extend outwardly from the frame 1 to facilitate shifting the slide bar 137. The slide bar 40 138 is operated in synchronism with the slide bar 137 by means of a lever 140 pivoted by a pin 141 to the cross bar 142 of the frame 1 so that when the slide bar 137 is moved in one direction the slide bar 138 is automatically moved in the 45 opposite direction. Any suitable means may be provided for securing the slide bars 137 and 138 in the adjusted position as, for example, the spring pressed detent 149 which fits into a hole in slide bar 137, preferably being releasable only 50 by drawing out handle 150. The belt 143 should, of course, be driven from a position equidistant from the two positions of the pulley on roll 96 to permit the reversing of the angularity of the rolls 96 and 97 as already described, and so that the 55 belt will be tight in both positions.

The lower feeding table 4 may be substantially the same as the feeding table 3 already described, although it has not been illustrated as reversible to turn the sheet in either direction at will.

60 *Additional folding units*

Although the folding units 10, 20 and 30 have each been illustrated as only a single folding unit, it should be understood that additional folders 65 may be provided at each position if desired. For example, at either or both of units 10 and 20 there may be two or more folders. Such multiple folding units are well known and therefore need not be specifically described. The arrangement of such multiple folding units should be such as to cause the sheet to pass through all sections thereof to form two or more parallel folds in the sheet or to skip all but one of the sections so as to form only one fold in the sheet 70 at this position.

Operation

When a flat sheet is fed along the table 2 to rolls 11 and 12, these rolls feed the sheet into buckle chute 13 until it strikes the paper stop 14, after which the sheet buckles and is caught between folding rolls 12 and 15 which feed the folded sheet between the scoring rolls 41 and 42 unless intervening folders are provided in connection with folding unit 10. If there is to be no subsequent folding, the scoring rolls 5 may 10 be separated so as not to score paper, and the deflector 46 at folding unit 10 is swung to the dotted line position shown in Fig. 1 to cause the sheet to be ejected at this point as indicated in 15 Fig. 14. In this event the stacking unit shown in Fig. 3 will be positioned to receive the sheet from this deflector 46 as indicated by the dotted lines adjacent deflector 46 in Fig. 1. It is thus seen that the sheet is removed from the machine 20 immediately after its folding is complete so that there is no chance for the machine to become jammed as the sheet passes subsequent folding units and no need to make adjustments in the rest of the machine. If the sheet is to be further folded, the deflector 46 below folding unit 25 10 is set in the position shown in full lines and the sheet passes onto the belt 95 which carries it along under the guide strip 101 and the guide extension 117.

If the next fold is to be at right angles to 30 the preceding fold, one end portion of the paper strikes the roller 128 and shoulder 116 which stop this end of the paper, causing the paper to be rotated through 90° as it is carried on by the belt 95, against which the paper is pressed firmly by the roller 124. After the sheet has been turned it is properly lined up for the next operation by being pressed against the edge guiding flange 115 due to the lateral inclination of the belt 95 in that direction. If the second fold 40 is to be parallel to the first fold, the sheet is not turned on the table 3. Turning may be avoided by replacing the sheet guide 111 with a plain sheet guide which does not have a roller 128 or stop 116, but instead has the edge guide 45 115 extending the length of the table 3. If the sheet guide 111 is retained, the roller 128 may be swung to an inactive position and the machine may be adjusted to cause the paper to strike the edge guide 115 after it has passed the stop 50 116. It will be understood of course that the feed table 2 will have an edge guide or jogger for determining the lateral position at which the sheet starts through folding unit 10 and hence its initial lateral position on the table 3. 55

The belt 95 now feeds the paper to the folder rolls 21 and 22 of folding unit 20 by which the sheet is fed into chute 23 until it strikes paper stop 24, at which time it buckles and is caught between rolls 22 and 25. From these it is fed 60 between the scoring rolls 6 which are separated so as not to score unless there is to be further folding. If there is no further folding, the deflector 46 below folding unit 20 is set to the position shown in dotted lines in Fig. 1 for ejecting 65 the completely folded paper at this point, the ejector shown in Fig. 3 having been moved to the position shown in dotted lines below the folding unit 20. Thus, if both folding units 10 and 20 are necessary to complete the folding of the 70 sheet but not unit 30, the folded sheet is ejected from the machine immediately after passing through the unit 20, as seen in Fig. 16, so that it need not pass through the unit 30.

If, however, the unit 30 is also needed, the 75

deflector 46 associated with folding unit 20 is set to the position shown in full lines in Fig. 1 and feeds the sheet to the feeding table 4 which carries it to the folding unit 30, turning it or not as may be required. The folding unit 30 makes the final fold in the sheet in the manner already described, after which the fixed deflector 47 directs the sheet to the ejecting rolls 48 and 49 of the stacking unit, which pass the folded sheet onto the intermittently moving belts 52 to stack the completely folded sheets in overlapping relationship as seen in Fig. 21.

From the foregoing and referring to Figs. 14 to 28 it is evident that the folding machine of this invention is capable of numerous combinations of folds even with only one folding unit at each folding station, and in each instance the folding is accomplished in the simplest possible manner. Thus, if a single fold is desired, the stacking unit is placed adjacent the first folding unit 10 as indicated in Fig. 14 and the sheets are folded as seen in Fig. 15 without passing through any of the remainder of the machine. Accordingly, no adjustments need be made in the remainder of the machine and there is no danger of the sheet jamming in passing subsequent folding units.

If the sheet is to be folded twice, the stacking unit 1 is placed adjacent the second folding unit 20 as seen in Fig. 16, thus making possible the various folds shown in Figs. 17 to 20 without necessitating any unnecessary adjustments and without danger of jamming due to passing idle folding units.

Similarly, if it is desired to fold the paper three times to form any of the folds shown in Figs. 22 to 28 or perhaps many others, the stacking unit 1 is positioned adjacent the folding unit 30 and the paper is folded successively by each of the three folding units (some of which may be double or triple folding units if desired). It is evident that since the sheet may optionally be turned 90°, both on table 3 and on table 4, a very large number of possible combinations of folds is available. Furthermore, with the belt 95 and edge guide member 111 in the position shown in full lines in Fig. 21 the sheet will be turned in one direction, while in the position shown in dotted lines in Fig. 21 the sheet will be turned in the other direction, thus providing still more varieties of folds. As seen in Figs. 26 and 28 a right-hand turn on table 3 and no turn on table 4 results in folding one end flap under while the other may be folded under by changing table 3 to make a left-hand turn.

I claim:

1. A folding machine adapted to make optionally a single fold, parallel folds, or right-angle folds, comprising a conveyor table, a folding unit at each end of the table, optionally effective sheet turning means associated with the table and positioned between the folding units, means between the first folding unit and the table for optionally causing a sheet from the folding unit to pass to the table or in a different direction, and a stacking unit optionally secured adjacent either of the folding units for receiving the sheet directly from said last named means or from the second folding unit.

2. A folding machine adapted to make optionally a single fold, parallel folds, or right-angle folds, comprising a conveyor table, a folding unit at each end of the table, optionally effective sheet turning means associated with the table and positioned between the folding units, means be-

tween the first folding unit and the table for optionally causing a sheet from the folding unit to pass to the table or in a different direction, and delivery means optionally secured adjacent either of the folding units for receiving the sheet directly from said last named means or from the second folding unit, said delivery means including a pair of rolls for seizing the sheets presented thereto and ejecting them from the machine.

3. A folding machine adapted to make optionally a single fold or a plurality of folds in a sheet, comprising a conveyor table, a first folder at the receiving end of the table, a second folder at the delivery end of the table, delivery means attachable in different positions for receiving folded sheets directly from each folder optionally, and means between the first folder and the conveyor table for optionally causing the sheets to pass to the conveyor table or to the delivery means.

4. A folding machine adapted to make a single fold or two folds at right angles in a sheet, comprising a conveyor table, a first folder at the receiving end of the table, a second folder at the delivery end of the table, means associated with the table and positioned between the folders for turning the sheet, delivery means attachable in different positions for receiving folded sheets directly from each folder optionally, and means between the first folder and the conveyor table for optionally causing the sheets to pass to the conveyor table or to the delivery means.

5. A folding machine adapted to make a single fold or two folds at right angles in a sheet, comprising a conveyor table, a first folder at the receiving end of the table, a second folder at the delivery end of the table, means associated with the table and positioned between the folders for turning the sheet, delivery means for receiving folded sheets directly from each folder optionally, and means between the first folder and the conveyor table for optionally causing the sheets to pass to the conveyor table or to the delivery means, each of the folders including drive gears, and said delivery means being readily detachable and attachable adjacent either folder and including drive gears which, upon attachment of the delivery means, mesh with the drive gears of the folder adjacent which the delivery means is attached.

6. A folding machine adapted to make optionally one, two or three folds, successive folds being optionally at right angles or parallel, comprising a pair of conveyor tables, a first folding unit at the receiving end of the first table, a second folding unit between the tables, and a third folding unit at the delivery end of the second table, means associated with each table and positioned between the folding units at the ends thereof for conveying the sheets along the table without turning if parallel folds are desired and for turning the sheet if right-angle folds are desired, delivery means attachable in different positions for receiving folded sheets directly from each folding unit optionally, and means between the first two folding units and the conveyor table following each respectively for optionally causing the sheets to pass to the conveyor table or to the delivery means.

7. A folding machine adapted to make optionally one, two or three folds, successive folds being optionally at right angles or parallel, comprising a pair of conveyor tables, a first

- 5 folding unit at the receiving end of the first table, a second folding unit between the tables, and a third folding unit at the delivery end of the second table, means associated with each 5 table and positioned between the folding units at the ends thereof for conveying the sheets along the table without turning if parallel folds are desired and for turning the sheet if right angle folds are desired, the turning means associated with the first conveyor table being optionally effective to turn the sheet in either direction, delivery means attachable in different positions for receiving folded sheets directly from each folding unit optionally, and means 10 15 between the first two folding units and the conveyor table following each respectively for optionally causing the sheets to pass to the conveyor table or to the delivery means.
8. A folding machine adapted to make optionally a single fold, right-angle folds, and parallel folds, comprising a conveyor table, a folding unit at each end of the table, optionally effective sheet turning means associated with the table and positioned between the folding units, and delivery means for receiving folded sheets at either end of the table, said delivery means permitting any one of the above mentioned types of folds to be delivered from the machine without substantially changing the direction of movement of the sheet except for making an additional fold or delivering the sheet from the machine.
9. A folding machine including a main frame, a pair of conveyor tables one above another carried by the frame, a folding unit carried by the frame at the discharge end of each of said tables, means associated with at least one of the tables optionally effective for turning a sheet thereon, adjustable deflector means carried by the frame adjacent to at least each of said folding units but the last for optionally directing the sheets onto the next table or away therefrom, and a single delivery unit including an auxiliary frame attachable to the main frame optionally adjacent 40 45 to each of said folding units and adapted to receive and deliver away from the tables any sheets deflected away from the tables; the main frame being provided with a pair of pins and a pair of holes at each attachment point, and the auxiliary frame having bifurcated members for engaging said pins and manually controlled pins for engaging the holes.
10. A folding machine for sheets adapted to make optionally a single fold, a plurality of parallel folds or a plurality of folds at an angle, including an initial folding unit, a subsequent folding unit adapted to receive the sheet from the initial folding unit, means for conveying the sheet longitudinally of the machine from one 50 55 folding unit to the next optionally effective for turning the sheet in its own plane to make a subsequent fold at an angle, a stacker for receiving the completely folded sheet and means positioned between the folding units for causing the sheet to pass to the said subsequent folding unit or optionally to the stacker.
11. A folding machine for sheets adapted to make optionally a single fold, a plurality of parallel folds or a plurality of folds at an angle, including an initial folding unit, a subsequent fold-
- ing unit adapted to receive the sheet from the initial folding unit, means for conveying the sheet longitudinally of the machine from one folding unit to the next optionally effective for turning the sheet in its own plane to make a subsequent fold at an angle, a stacker for receiving the completely folded sheet and means positioned between the initial folding unit and the conveying means for causing the sheet to pass to the next folding unit or optionally to the stacker 10 15 without traversing the conveying means.
12. A folding machine including a series of folding units all adapted to move the sheet longitudinally of the machine, conveying means for conveying the sheet between folding units and 20 25 adaptable to turn the sheet if desired before each fold after the first to cause each subsequent fold to be optionally either parallel to or at an angle to the first fold, a stacker, and means for causing the sheet to pass from any folding unit directly to the stacker whereby the folding units may be used in order until the desired number of folds have been made regardless of the direction of the folds with the result that no adjustment is necessary for the folding units or conveying means located beyond the folding unit with which the stacker is associated.
13. A folding machine including a main frame, a pair of conveyor tables one above another carried by the frame, a folding unit carried by the frame at the discharge end of each of said tables, means associated with at least one of the tables optionally effective for turning a sheet thereon, adjustable deflector means carried by the frame adjacent to at least each of said folding units 30 35 but the last, for optionally directing the sheets onto the next table or away therefrom, and a single delivery unit including an auxiliary frame attachable to the main frame optionally adjacent each of said folding units and adapted to receive and deliver away from the tables any sheets deflected away from the tables.
14. A folding machine adapted to make optionally a single fold, right angle folds, and parallel folds, comprising a conveyor table, a folding unit at each end of the table, optionally effective sheet turning means associated with the table and positioned between the folding units, delivery means for receiving folded sheets at either end of the table, deflecting means positioned between the receiving end of the table and the associated folding unit, said deflector means being optionally effective for deflecting a folded sheet from the associated folding unit to the receiving end of the table or to the delivery means.
15. A folding machine adapted to make a single fold or two folds at right angles in a sheet, comprising a conveyor table, a first folding unit comprising a single folder at the receiving end of the table, a second folding unit at the delivery 60 65 end of the table, means associated with the table and positioned between the folding units for turning the sheet, delivery means attachable in different positions for receiving folded sheets directly from each folding unit optionally, and means between the first folding unit and the conveyor table for optionally causing the sheets to pass to the conveyor table or to the delivery means.
